UNITED STATES PATENT OFFICE

2,557,242

ELECTROMAGNETIC VIBRATORY
ADVERTISING DEVICEJoseph A. Simpson, New York, N. Y., assignor of
one-half to Maria Hearst, New York, N. Y.

Application December 9, 1948, Serial No. 64,338

4 Claims. (Cl. 40—52)

1

This invention relates generally to advertising devices and more particularly to an advertising device including one or more display units having decorated objects animated to move relative to fixed decorated panels, together with motorized switch means of special design to control electric currents through electro-magnets operatively associated with the said decorated objects.

A primary object of this invention is to provide a means whereby the electric currents through the said electro-magnets can be varied both as to order and duration, with respect to the different electro-magnets, thus allowing a very wide variation in the type of animation achieved.

Still another object of this invention is to provide means whereby a considerable number of different display units can be operated simultaneously by a single control unit, the different display units and the control unit being spaced widely apart when required, as when the control unit is in one room or window and the different displays are in still other rooms or windows.

Still another object of this invention is to provide means whereby a decorated object may be merely made to vibrate or quiver, to move successively into different positions, and to be held in such positions for any predetermined length of time.

Still another object of this invention is to provide specific means for carrying out the above mentioned general objects.

An inexpensive advertising device in which all parts thereof are simple to manufacture or of conventional character, which is simple, safe and completely practical to operate, and which will give generally efficient and durable service.

With these objects definitely in view, this invention resides in certain novel features of construction, combinations and arrangements of elements and portions as will be hereinafter described in detail in the specification, particularly pointed out in the appended claims, and illustrated in the accompanying drawings which form a material part of this application, and in which:

Figure 1 is a vertical sectional view representing a single display and a control unit therefor, which structure is part of a larger assembly represented in the three-dimensional view in Figure 7;

Figure 2 is a front elevational view of the control unit with the electrical lead wires shown fragmentarily and the casing for the unit shown in vertical section;

Figure 3 is a similar view taken from the side of the control unit;

2

Figure 4 is a fragmentary rear view of a display unit such as one of those display units illustrated in Figure 7;

Figure 5 is a similar fragmentary rear view of another of the display units;

Figure 6 is a schematic view showing a representative portion of the wiring diagram used in this invention; and,

Figure 7 is a three-dimensional view showing 10 a control unit and the display units above mentioned.

Similar characters of reference designate similar or identical elements and portions throughout the specification and throughout the different 15 views in the drawings.

Referring now to the drawings in detail, this invention will include a display unit, generally indicated at 10, having a decorated panel 12 and another panel 14 disposed parallel thereto, both 20 panels being represented as being vertical. Within the display case 10 and between the panels 12 and 14 there is mounted an elongated resilient member 16 which may be of either strap or rod form and which has its lower end 18 fixed in 25 a block 20 which is, in turn, mounted upon any suitable portion of the display unit 10 as indicated generally at 22.

A decorated object 24 is mounted upon the upper end of this resilient member 16 so as to 30 be visible and to move in a predetermined arc when the resilient member is made to move. The resilient member has a plurality of laterally extending arms 26, 28, 30 and 32, rigidly secured thereon in longitudinally spaced relation and 35 these arms are of magnetic or magnetizable material and positionally related to electro-magnets 34, 36, 38 and 40 so that energization of these electro-magnets will cause a corresponding movement in the resilient member 16 and decorated objects 24 carried thereby. In the embodiment illustrated, the electromagnets are mounted upon the panel 14 and disposed thereon so that selective energization of the electro-magnets will result in different movements of 40 the resilient member 16. For example, energization of the electro-magnet 36 with the other electro-magnets not energized will cause the resilient member to move from a neutral position toward the right in Figure 1. If now the electro-magnets 38 and 40 are successively energized the 45 decorated object 24 will be moved successively to the right into the final position indicated in dash lines in Figure 1. Upon release of the electro-magnets 36, 38 and 40 and the energization 50 of the electro-magnet 34, the arm 26 will 55

be attracted to the electro-magnet 34 when the resilient member 16 swings to the left. It will also be obvious that a vibratory motion in the resilient member 16 may be set up as by the energization of the electro-magnet 36 when the resilient member is in neutral position and if the electro-magnet 36 is then de-energized the resilient member will continue to vibrate for a certain length of time due to its own resiliency. It follows, that a considerable number of distinctive motions may be attributed to a decorated object such as that indicated at 24 with relation to a fixed panel and it will of course be obvious that the character of such decorations will be not limited to such devices as that represented in the drawings.

The control unit for the device may be mounted within a casing 52 and electrical leads 42 will connect the electro-magnets to a transformer 44 connected as indicated at 46 with power lead-in wires 47 of any other analogous and suitable source of electrical energy. Other electric lead wires will connect the electro-magnets with a plurality of brushes 50 adjustably mounted on a support, generally indicated at 54, mounted within the casing 52.

An electric motor 46 is mounted on another bracket support 57 within the casing 52 and a disc 58 of metallic material is mounted on the drive shaft of the motor 56. One side of the disc 58 is partially covered with insulated material 60 and certain arcuate portions 62, 64 and 66 are left uncovered, and it will be noted that the disc is so mounted that the brushes 50 may contact these uncovered portions 62, 64 and 66 of the disc when the disc is rotated. In this connection it should be noted that the electric motor 56 will, in practice, have incorporated therewith reduction gearing whereby the speed of rotation of the disc 58 is reduced as required, unless the motor and disc are otherwise adapted to turn rather slowly. The support generally indicated by the numeral 54 is of special construction and includes an upright 68 vertically slotted at 70, along with a cross beam 72 which is longitudinally slotted, and a bolt and wing nut assembly 74 is inserted through the said slots so that the cross beam can be shifted relative to the upright 68. Another brush 76 will be secured by a screw 78, the previously mentioned brushes 50 being also similarly secured to the upright 68, and still another brush 80 will be rigidly mounted within the casing 52 to bear against the opposite side of the disc 58, this last mentioned brush 80 being connected in the embodiment illustrated with the transformer 44, so that intermittent surges of current will be transmitted to the electro-magnets mentioned above, when the disc 58 is rotated by the electric motor.

Still other portions 82 of the disc 58 will be left uncovered by insulation and the same brushes may be used to transmit intermittent electric currents to still other electro-magnets such as that represented in another display unit 83 indicated in Figures 4 and 7.

This second display unit 83 may contain an elongated resilient member 84 similar to that already described and similarly mounted within a case having a panel 86 apertured as at 88 to represent, for example, an eye member of an animal when the panel 86 is decorated in any such manner as indicated in Figure 7, it being understood that this structure is merely illustrative of one adaptation of this invention. The resilient member 84 will carry a decorated object

90 secured by any suitable fastening means indicated at 92 upon an intermediate portion of the resilient member, and the decorated object 90 will be positioned to move in an arc so as to be visible through the aperture 88 in the panel 86. An electro-magnet 94, connected to the control unit already described by electric lead wires such as those already identified by the numeral 48, will be positioned adjacent to an arm 96 integral with or carried by the resilient member 84, and it will be noted that the electro-magnet is also placed immediately outside the arc described by the arm 96 when the resilient member 84 oscillates. It should be carefully noted that the arm 96 corresponds very closely with the arms 26, 28, 30 and 32, except that the positional relationship of the arm and the electro-magnet is such as to allow free oscillation of the resilient member 84 and the decorated object 90 carried thereby so that a quivering motion may be imparted to the decorated object.

In the display unit generally indicated at 98 in Figures 5 and 7 a panel 100 is apertured at 102 to allow visibility of an animated decorated object 104 carried on a resilient member 106 which, like the resilient members already described, is provided with laterally extending arms 108 of magnetic or magnetizable material. A pair of electro-magnets 110 are disposed on either side of the resilient member 106 to attract the arms 108. This construction is somewhat analogous to the construction involving the electro-magnets 34 and 36 in Figure 1 and it should be noted that the decorated objects may be made to move in either of two directions and either held fixed in either of two positions or thereafter allowed to vibrate under the action of the elongated resilient member. It may be particularly noted that, in Figure 5, there is represented means 112 to limit the movement of the resilient member 106 in either direction, this means being either a pair of pins or a staple carried by the decorated panel and positioned so as to prevent the arms 108 from actually contacting the electro-magnets 110. By the use of this means 112 the arms are prevented from clinging to the electro-magnets after the current is interrupted to the electro-magnets concerned due to residual magnetism, and it will be understood that the simple means 112 may be used with any one of the resilient members. Finally it may be noted that, in Figure 7 the numeral 49 has been used to indicate the cables in which the lead wires 42 and 48 are collected.

The operation of this invention will be clearly understood from a consideration of the drawings, taken in connection with the above recitation of the objects to be achieved by this invention and the foregoing description of the mechanical details thereof, and further description would appear unnecessary.

Having described the invention, what is claimed as new is:

1. An advertising device comprising a display unit including a decorated fixed panel, a resilient elongated member having one end supported in fixed relation to said panel and the other end free to vibrate, a decorated object carried by said other end of the resilient member, a plurality of electro-magnets fixed on said unit adjacent to said resilient member and spaced along said resilient member, portions of said resilient member adjacent said electro-magnets being of magnetic material, with a source of power so that said electro-magnets will be intermittently and progressively energized and said resilient member

and decorated object activated to move progressively in one direction.

2. An advertising device comprising a display unit including a decorated fixed panel, a resilient elongated member having one end supported in fixed relation to said panel and the other end free to vibrate, a decorated object carried by said other end of the resilient member, a plurality of electro-magnets fixed on said unit adjacent to said resilient member and spaced along said resilient member, said resilient member having a plurality of portions of magnetic material each comprising a laterally extending arm and each operatively associated with one of said electro-magnets, whereby the resilient member may be consecutively moved into a corresponding plurality of positions.

3. A device according to claim 2 and wherein said plurality of arms are spaced longitudinally along one side of said resilient member and the corresponding electro-magnets are arranged to attract the last mentioned arms consecutively to move said resilient member in progressive stages in one direction.

4. An advertising device comprising a display unit including a decorated fixed panel, a resilient elongated member having one end supported in

fixed relation to said panel and the other end free to vibrate, a decorated object carried by said other end of the resilient member, a plurality of electro-magnets fixed on said unit adjacent to said resilient member and spaced along said resilient member, portions of said resilient member adjacent said electro-magnets being of magnetic material, an intermittent switch connected with said electro-magnets and a source of power so that said electro-magnets will be intermittently and progressively energized and said resilient member and decorated object activated to move progressively in one direction.
